TELEPHONE INDEX HOLDER

Edmond J. Huott, New York, N. Y.

Application July 22, 1936, Serial No. 91,860

9 Claims. (Cl. 40—10.5)

This invention relates to new and useful improvements in a telephone index holder.

The invention has for an object the construction of a device as mentioned which is characterized by a support plate having a pair of finger portions adapted to extend across the tops and front faces of the fingers of a French or Cradle telephone, and having loops associated with a base plate removably supported in a novel manner.

Still further the invention contemplates the provision of an index holder mounted upon the base plate and adapted to be encased within a cover removably mounted on the base plate and cooperating to lock the base plate in position in the support plate.

Still further the invention proposes the provision of a means for locking the base plate on the support plate when the cover is in position.

Another object of the invention resides in an arrangement for locking the finger portions on the fingers of the French or Cradle telephone when the cover is in position.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a front elevational view of a French or Cradle telephone with a telephone index holder constructed according to this invention.

Fig. 2 is an edge elevational view of Fig. 1.

Fig. 3 is an horizontal sectional view taken on the line 3—3 of Fig. 1.

Fig. 4 is a perspective view of the cover for the index holder, illustrated per se.

Fig. 5 is a perspective view of the index holder with the cover removed.

Fig. 6 is a sectional view taken on the line 6—6 of Fig. 1.

Fig. 7 is a rear elevational view of Fig. 1.

The telephone index holder, according to this invention, comprises a support plate 10 having a pair of finger portions 10^a adapted to extend across the tops and the front faces of the fingers 11^a of a French or Cradle telephone 11. These finger portions 10^a are provided with loop portions 12 adapted to partially encase the fingers 11^a. A base plate 13 is removably supported on the support plate 10. An index holder 14 is mounted on the base plate 13. A removable cover 15 is adapted to encase the index holder.

A means is provided for locking the base plate 13 on the support plate 10 when the cover is in position. Another means is provided for locking the finger portions 10^a upon the fingers 11^a of the

telephone, also when the cover 15 is in position. These means will be described in detail hereinafter.

The support plate 10 is formed with an upward curled portion 16 between the finger portions 10^a comprising a support for a pencil. The finger portions 10^a are bent at an inclination to the body portion of the support plate 10 as clearly shown in Figs. 2 and 6. The object is to give the index holder a backwardly inclined position, so that it is convenient to refer to when desired.

The base plate 13 is formed with several bayonet slots 18 spaced inward from the top edge thereof. Several studs 19 are fixedly mounted on the support plate 10 and are adapted to engage the bayonet slots 18 for holding the base plate removably on the support plate. The studs 19 are formed with slots 20 which are adapted to be engaged by lug portions 21 stamped from the top wall of the removable cover 15. The base plate 13 has outwardly extending side walls 23. From the top and bottom edges of these side walls small lugs 24 project and are adapted to engage the innerwalls of the removable cover 15. These lugs 24 form guiding elements to properly hold and position the cover 15. When the cover 15 is forced into position the lugs 21 engage the slots 20 and so the base plate 13 is held against lateral motion which is requisite for its removal from the support plate. When the top 15 is in its proper position with the lugs 21 engaging the slots 20 it acts as a locking device by preventing the studs from moving laterally in the bayonet slots 18. Thus when it is desired to move the base plate 13 one must first move the cover 15 and then move the plate 13 to disengage the studs 19 from the bayonet slots 18 to separate the plates 10 and 13.

The index holder 14 comprises a web of index material 14^a wound upon a top roller 25 and a bottom roller 26. The web portion of the material 14^a engages over a flat strip 27 which is secured at its ends upon the edges of the side walls 23. This support strip 27 is located immediately behind a window opening 28' formed in the cover 15 when the cover is properly positioned on the device. Each of the rollers 25 and 26 are rotatively supported on the side walls 23 and each is equipped with a small pinion 28 which meshes with a small gear 29 fixed upon a stud shaft 30 rotative through one of the walls 23. A handle 31 is fixed on the outer end of the stud 30. The arrangement is such that the handle 31 may be turned in one or the other direction to wind the web 14^a from one to the other of the rolls, or vice versa.

The cover 15 is formed with an opening 29 through which the stud shaft 30 may pass when the cover is pressed on the device. The web 14 is imprinted with a plurality of spaced lines 60

32 which are indicated by letters 33 along one of the sides.

The loop portions 12 extend outwards from the inner edges of the finger portions 10^a. Each 5 of the loop portions 12 is formed with a cutout portion 38 which provides room so that the conventional hook element 39 of the French or Cradle phone may move to its upward position when the receiver is removed. Each of the finger 10 portions 10^a is formed with an opening 40 through which a head element 41 projects. These head elements are mounted upon one of the studs of the levers 42 which are pivotally mounted intermediate of their ends by pintles 43. The 15 other ends of these levers 42 extend over openings 44 formed in the support plate 25. Projecting portions 45 from the base plate 13 extend through the openings 44 and in the normal position of the base plate engage beneath the levers 20 42 to hold them pivoted so that the heads 41 engage beneath the out-turned ends and the fingers 11^a of the French or Cradle telephone and so lock the device upon the telephone.

Before the device may be removed from the 25 telephone it is necessary that the cover 15 be removed and then the base plate 13 be moved laterally to the support plate 10 to disengage the base plate from the bayonet slots 18. At the same time the projections 45 will move free from 30 the levers 42 which may then be pivoted so that the heads 41 disengage from the fingers 11^a of the French or Cradle telephone.

While I have illustrated and described the preferred embodiments of my invention, it is to 35 be understood that I do not limit myself to the precise constructions herein disclosed and the right is reserved to all changes and modifications coming within the scope of the invention as defined in the appended claims.

40 Having thus described my invention, what I claim as new, and desire to secure by United States Letters Patent is:—

1. A telephone index holder comprising a support plate having a pair of finger portions each 45 having a loop portion adapted to encompass a finger of a French or Cradle telephone, a base plate removably supported on said support plate, an index means mounted on said base plate, and a removable cover for said index means.

50 2. A telephone index holder comprising a support plate having a pair of finger portions each having a loop portion adapted to encompass a finger of a French or Cradle telephone, a base plate removably supported on said support plate, 55 an index means mounted on said base plate, and a removable cover for said index means, said loop portions being formed with cutouts which provides sufficient clearance to allow the hook of a French or Cradle telephone to be removed and allow the device to operate properly.

60 3. A telephone index holder comprising a support plate having a pair of finger portions each having a loop portion adapted to encompass a finger of a French or Cradle telephone, a base plate removably supported on said support plate, 65 an index means mounted on said base plate, and a removable cover for said index means, said base plate having bayonet slots extended in from its top edge which engage studs from the support plate for removably connecting these parts.

70 4. A telephone index holder comprising a support plate having a pair of finger portions each having a loop portion adapted to encompass a

finger of a French or Cradle telephone, a base plate removably supported on said support plate, an index means mounted on said plate, and a removable cover for said index means, said base plate having bayonet slots extended in from its top edge which engage studs from the support plate for removably connecting these parts, said cover having several lugs engageable in slots formed in the heads of said studs to prevent the base plate from being moved laterally and so locking the base plate and support plate together. 5

5. A telephone index holder comprising a support plate having a pair of finger portions each having a loop portion adapted to encompass a finger of a French or Cradle telephone, a base 15 plate removably supported on said support plate, an index means mounted on said base plate, a removable cover for said index means, and means for locking said base plate on said support plate when the cover is in position. 20

6. A telephone index holder comprising a support plate having a pair of finger portions each having a loop portion adapted to encompass a finger of a French or Cradle telephone, a base 25 plate removably supported on said support plate, an index means mounted on said base plate, a removable cover for said index means, and means for locking said base plate on said support plate when the cover is in position, including lugs stamped from the cover and engaging slots in 30 the heads of studs mounted in the base plate and said studs being engageable in bayonet openings in the base plate.

7. A telephone index holder comprising a support plate having a pair of finger portions each 35 having a loop portion adapted to encompass a finger of a French or Cradle telephone, a base plate removably supported on said support plate, an index means mounted on said base plate, a removable cover for said index means, and means 40 for locking said finger portions on the fingers of said telephone when the cover is in position.

8. A telephone index holder comprising a support plate having a pair of finger portions each having a loop portion adapted to encompass a 45 finger of a French or Cradle telephone, a base plate removably supported on said support plate, an index means mounted on said base plate, a removable cover for said index means, and means for locking said finger portions on the fingers of 50 said telephone when the cover is in position, comprising pivoted levers mounted upon said fingers and having heads engageable against the out-turned ends of the fingers of the French or Cradle telephone, and means for locking said levers in 55 operative positions.

9. A telephone index holder comprising a support plate having a pair of finger portions each having a loop adapted to encompass a finger of a French or Cradle telephone, a base plate removably supported on said support plate, an index means mounted on said base plate, a removable cover for said index means, and means for locking said finger portions on the fingers of 60 said telephone when the cover is in position, comprising pivoted levers mounted upon said fingers and having heads engageable against the outturned ends of the fingers of the French or Cradle telephone, and means for locking said levers in 65 operative positions, including projections from the base plate engaging through slots in the support plate and engaging said levers. 70
